UNITED STATES PATENT OFFICE.

GEORGE C. COLEMAN, OF TERRE HAUTE, INDIANA.

ADJUSTABLE PIN AND GUIDE FOR MOLDERS' FLASKS.

Application filed December 8, 1925. Serial No. 74,070.

The invention relates to molders' flasks of the two-piece type comprising a "drag" and a "cope".

In flasks of the type stated, it is customary to provide the drag with a pin and the cope with a guide engaging the pin so that after the impression is made and the cope is removed to lift the pattern from the mold, the cope may be returned to its identical original position so that a perfect casting may be made. As the pins and guides wear by use it will be apparent that eventually the engagement between the pins and guides will be imperfect. Furthermore, in long use of the flask the drag will expand so that adjustment of the pins and guides would be necessary.

Heretofore it has been the practice to effect the adjustment by inserting pieces of card-board under the attaching means of the pins or guides, as the case may be, in order to make a close fit between the guides and pins. This practice has not been uniformly satisfactory because the card-board is likely to be moistened by the moisture used in the forming of the mold, and furthermore the means for holding the pins and guides on the flask, usually consisting of wood screws are likely to wear large holes in the ends of the flask that have to be plugged, and in any event the adjustment is unsatisfactorily accomplished.

This invention has for its object the provision of means by which the pin and guide may be quickly adjusted without removal from the ends of the flask and consists primarily in the provision of plates fixedly secured to the ends of the cope and drag and having the pins and guides mounted for adjustment relatively to said plates and providing set screws to enable a fine adjustment of the parts for a most successful operation of the flask.

The invention has for a further object the provision of a bearing on the pin to engage the guide that is offset outwardly from the pin to prevent wearing of a portion only of the pin and thus forming a rib or ridge on the pin that would require drilling or filing the pin to remove.

The invention will be described in detail hereinafter and will be found illustrated in the accompanying drawings, in which

Figure 1 is an end view of a snap flask

with the improved pin and guide in position thereon, 55

Figure 2, a vertical sectional view on the plane indicated by the line 2—2 of Figure 1, showing the parts on an enlarged scale,

Figure 3, a similar vertical sectional view 60 on a plane indicated by the line 3—3 of Figure 1,

Figure 4, a horizontal sectional view on a plane indicated by the line 4—4 of Figure 1,

Figure 5, a similar view on a plane indicated by the line 5—5 of Figure 1, 65

Figure 6, a similar view on a plane indicated by the line 6—6 of Figure 1,

Figure 7, a detail sectional view on a plane indicated by the line 7—7 of Figure 5, 70

Figure 8, a horizontal sectional view on a plane indicated by the line 8—8 of Figure 1,

Figure 9, a perspective view of the guide,

Figure 10, a similar view of the pin showing the upper portion thereof broken away, 75 and

Figure 11, a similar view of the plate carrying the guide.

In the drawings similar reference characters will be used to designate corresponding parts throughout the several views.

In Figure 1 is shown the end view of a molder's snap flask in which the letter A indicates the top or cope portion of the flask, while B indicates the base or drag. Secured to the drag portion B is a plate 1 secured thereto by screws 2 or other suitable means, and said plate 1 is provided with bosses 3 having threaded openings 4 therein, said bosses seating in openings 5 in the ends of the drag B. Secured to the plate 1, by means of screw bolts 5 engaging through enlarged openings 6 in the offset flanges 7, is a pin 8 connected with said flanges 7 by means of arms 9, said pin 8 being V-shaped in cross section as shown, and the outer surface thereof offset from the remainder of the outer face of the pin as shown at 10 to form a bearing for the guide to be herein-after described. It will be apparent that the enlarged openings 6 in the flanges 7 provide for a limited adjustment sidewise and up and down of the pin 8 relatively to the plate 1 and the drag 2, said adjustment being held by means of the screw bolts 5 engaging the threaded openings 4 in the plate 1 and bosses 3. A further adjustment of the pin relatively to the plate 1 and the drag B,

105

is secured by means of set screws 11 having socket openings as shown to enable actuation of the set screws, said screws being arranged adjacent the outer corners of the off-
5 set flanges 7.

It will be apparent from this construction that the pins 8 may be adjusted toward and from the drag B by proper movement of the screws 11 to insure proper positioning of the pin relatively to the drag, and as heretofore stated, the pin may be shifted sideways or up or down as may be required for the proper adjustment thereof, all adjustments being maintained by tightening on the
10 bolts 5. Secured to the cope A is a plate 12 by means of screws or other driven fastenings 13, and having a boss 14 located at each side of the vertical center of the plate, each of said bosses having a threaded opening 15. Above and below each boss 14 is an enlarged portion 16, each of which carries a polygonal headed cap screw 17. The guide comprises a V-shaped portion 18 adapted to slidably engage the bearing surface 10 of the pin 8 and having offset flanges 19 with enlarged openings 20 to receive bolts 21 engaging the threaded openings 15 in the bosses 14 to secure the guide on the plate 12, the enlarged openings 20 admitting of adjustment of the guide sideways and up and down, and being held in adjusted position by tightening the bolt 21, the inner faces of the flanges 19 being also engaged by the headed set screws 17 to adjust the
25 guide in and out from the plate 12.

From this description it will be apparent that the pins 8 and the guides 18 may be accurately adjusted to insure returning the cope in exactly the same position relatively
40 to the drag for forming the casting after removal of the cope from the drag to remove the pattern from the mold, 21 indicating an outwardly directed flange on the guide, and flanges 19 to form a hand hold for handling
45 the cope.

What is claimed is:—

1. Guiding means for two part molding flasks, comprising a plate adapted to be secured to one of the members of a flask, bolts 50 engaging said plate, a pin, flanges on said pin and mounted on said bolts, set screws engaging said flanges and adapted to engage the plate to adjust the position of said pin,

and a guide adapted to be secured to the other member of a flask and to slidably engage the pin.
55

2. Guiding means for two part molding flasks, comprising a pin adapted to be adjustably secured to one of the members of a molding flask, a plate adapted to be secured to another member of the flask, said plate having threaded bosses, bolts engaging said threaded bosses, set screws engaging said plate, and a guide having a bearing surface adapted to engage said pin, said guide mounted on the bolts aforesaid and engaging said set screws.
60

3. In guiding means for two part molding flasks, a plate to be secured to one part of a flask, a pin, flanges on said pin, bolts 70 secured to the plate, the flanges having openings larger than the diameter of the bolts and adapted to receive said bolts and set screws threadedly engaging the flanges and abutting the plate to adjust the pin relatively to the plate, the enlarged openings in the flanges also permitting limited adjustments 75 of the pin vertically and horizontally.

4. In guiding means for two part molding flasks, a plate to be secured to one part of a flask, a guide, flanges on said guide, bolts secured to the plate, said flanges having openings larger than the diameter of the bolts and adapted to receive said bolts and set screws threadedly engaging the plate and 80 abutting the flanges to adjust the guides relatively to the plate, the enlarged openings in the flanges permitting adjustments of the guide horizontally and vertically.
85

5. Guiding means for two part molding flasks, comprising a plate to be secured to each part of a flask, a pin, flanges on said pin, threaded members engaging said flanges and one of the plates to hold the pin on the plate, set screws threaded into the flanges 90 and engaging the plate to adjust the pin relatively to the plate, a guide, flanges on the guide, threaded members engaging said flanges and the other plate to hold the guide on the plate, and set screws threaded into the plate and engaging the flanges to adjust the guide relatively to the plate.
95

In testimony whereof I affix my signature.

GEORGE C. COLEMAN.
